PINKING DEVICE

Victor J. Sigoda, Brooklyn, N. Y., assignor to Man-Sew Pinking Attachment Corporation, New York, N. Y., a corporation of New York

Application September 2, 1937, Serial No. 162,111

37 Claims. (Cl. 164—175)

This invention relates to pinking devices, more particularly to pinking devices that may be used in connection with industrial sewing machines for pinking the edges of work during the operation in which the work is stitched or sewed by the sewing machine.

The invention has for an important object the provision of a construction of means whereby at will the work may be trimmed or pinked at a variable, predetermined distance in laterally spaced relation from the seam or line of stitching. In other words, by my present invention the width of the pinked edge or edges, extending laterally from the seam or line of stitching, may be increased or diminished as best suits the nature and character of the work.

The invention also comprehends a novel mechanism and method of producing an undulating pinking edge on the fabric as it is progressively moved or fed in a rectilinear path, in which the pinking cutter rotates in a plane which is parallel to the plane of the fabric.

Another object of the invention is the provision of a device of the character referred to, so devised and arranged that I may employ therein as an efficient bottom pinking cutter the general type of flat circularly closed horizontally rotatable pinking ring heretofore invented by me and a form of which is disclosed in my application Serial Number 45,787, filed October 19, 1935.

In the embodiments of my invention as herein shown, for simplicity, ease of operation and reliability, the ring cutter is eccentrically mounted for rotary operation in a carrier plate which is itself mounted for rotary movement whereby the rotation of said plate will change the position of the point of pinking occurrence in relation to the line of stitching.

A further object of the invention is the provision of a form of construction whereby through the rotation of the carrier plate, the eccentrically mounted pinking cutter, when simultaneously rotated about its own axis, will produce an undulated or wavy pinked edge on the goods.

Two examples constituting practical embodiments of my invention are illustrated in the accompanying drawings. In one example, provision is made for manually rotating or adjusting the carrier and for locking the same stationary in the position desired, preparatory to operating the pinking cutter for pinking the work.

In the other example, provision is made for independently and simultaneously rotating the carrier and cutter when it is desired to produce undulating pinking, and further for locking the car-

rier stationary in the position selected when it is desired to operate the cutter alone.

Other objects will appear hereinafter.

The invention consists in the construction, combination and relative arrangement of parts herein described and claimed.

The invention will be best understood by reference to the accompanying drawings, forming a part of this specification, and in which:

Fig. 1 is a top plan view of a pinking device 10 made in accordance with my invention and shown as provided with manually operated means for adjusting the pinking ring carrier;

Fig. 2 is a vertical sectional view taken on the line 2—2 of Fig. 1;

Fig. 3 is a vertical sectional view taken on the line 3—3 of Fig. 1;

Fig. 4 is another top plan view of the pinking device, this view showing the same as it appears when equipped with power operated means for driving the carrier to produce undulating pinking;

Fig. 5 is a vertical sectional view taken on the line 5—5 of Fig. 4;

Fig. 6 is a partial plan and sectional view, showing the driving mechanism including the clutches 25 for simultaneously operating the pinking ring and its carrier;

Fig. 7 is a vertical sectional view taken on the line 7—7 of Fig. 4 and

Fig. 8 is a fragmentary view of a piece of fabric, 30 showing the same pinked with an undulating edge.

Referring first to Figs. 1, 2 and 3, wherein I have shown an embodiment of the invention for purposes of illustration, 10 denotes a base plate which is applied to the cloth plate 11 or other support for the sewing machine. The base plate 10 is provided with a throat plate 12 in which is a slot 13 for the operation of the usual four-motion feed-dog 14, and also in which is an opening 15 for the operation of the sewing needle.

Mounted for rotation in an appropriate recess 16 in the top of the base plate is a circular carrier plate or adjustable support 17 the depending hub 18 of which has turning fit in a boss or bearing 19 provided for the purpose on the base plate. 40 Fitted eccentrically in the hub 18 for rotary movement is a shaft 20, its upper end being formed with or secured to, a pawl-carrying disc 21 arranged to rotate in an eccentrically located circular recess 22 provided in the top of the carrier 45 17. The recess 22 is of a size to provide an annular space between the outer periphery of the pawl-carrying disc 21 and the outer wall 23 of the recess. This space provides a raceway 24 in which upon roller bearings 25 or other suitable anti-friction

55

means is mounted the pinking ring 26 with its top or upwardly facing pinking teeth 27. As clearly shown in Fig. 1 the pawl-carrying disc and the pinking ring are arranged to have concentric relation with respect to the vertical shaft 20.

The pinking ring is operated intermittently in the direction of the arrow 28 and in synchronism with the feeding strokes of the feed dog 14. To this end, power may be taken from the feed dog operating rock shaft 29 of the sewing machine. This rock shaft is operated in the usual way from an eccentric on the main shaft (not shown), through links 30 and 31. The movement of the rock shaft is transmitted through crank 32, feed bar 33, feed arm 34 and shaft 20 to the pawl-carrying disc 21 which is thereby given a rotary oscillating motion. In the present embodiment, the pinking ring has around its inner periphery an upstanding flange 35; and the disc is provided with pivoted pawls 36 in openings 37, which pawls have outer hooked ends 38 for interengaging with the flange 35. When the disc is moved in the direction of the arrow 28, the flange is gripped by the pawls and the pinking ring is moved, and springs 39 associated with the pawls are compressed. On the reverse movement of the disc the spring-urged pawls slip on the flange, and in this connection it is to be observed that a spring-urged pawl 40 pivoted to a check plate 41 positively prevents any reverse movement of the pinking ring. By this arrangement, it will be appreciated that the usual to and fro movement of the feed mechanism of the sewing machine may be used to drive the pinking ring intermittently.

In Fig. 1, it will be noted that the dash-dot line 42 indicates the line of stitching fed rearwardly by the feed-dog from the position of the sewing needle which produces the stitching. It is in respect of this line that it is desired to adjust the pinking ring so as to vary the lateral range of the pinked edge from the sewing.

To achieve this end, the outer periphery of the carrier 17 is toothed or milled at 43, and I mount on the base-plate a manually operated pinion 44 the teeth of which are in mesh with the teeth of the carrier. The carrier is normally locked by a locking nut 45. By releasing this locking nut and turning the pinion, the carrier may be turned to that position in which the eccentrically mounted pinking ring will function to trim the work at the desired lateral range or distance from the line of stitching. Naturally in this arrangement, the lateral range or distance of the trimmed edge from the line of stitching is limited by the eccentric throw of the carrier.

The top of the structure is closed by a cover-plate 46 attached to the carrier by screw pins 47 which pass through slots 47' in the disc. The means for pressing the work downwardly upon the teeth of the pinking ring comprises a rotatable roller 48 carried by an arm 49 projecting from a rock shaft 50 which is mounted in bracket 51 for rocking movement under pressure of the material on roller 48. Such movement of the rock shaft 50 is controlled by an adjustable device 52 similar to that disclosed in my prior application, above identified, for the purpose of regulating the pressure of roller 48 upon the material. Preferably and as shown the face of the roller 48 in an axial direction is of sufficient extent to accommodate a substantial adjustment of the pinking ring from the sewing line. The bracket 51 is also adjustable upon the base plate 75 in order to position the roller relative to the

cutter teeth 27, said bracket being provided with elongated slots 53 and thumb screws 54.

In the form of construction shown in Figs. 4 to 7 inclusive, provision is made for operating the carrier and the pinking ring together by power means in order to produce on fabric as 55 an undulating pinked edge 56 laterally from a line of stitching 57. In this construction, 58 represents the base plate, 59 the feed dog, 60 the feed line of stitching, 61 the carrier, and 62 the eccentrically mounted pinking ring. Power is illustrated as taken from the rock shaft 63 which may form part of the usual feed mechanism of the sewing machine.

The pinking ring is intermittently operated 15 from the rock shaft 63 through vertical shaft 64, intermittent clutch 65, feed bar 66, ball joint 67, link 68, ball joint 69 and feed arm 70 which is connected with the rock shaft. The carrier is operated with the pinking ring, from the said 20 rock shaft 63 through pinion 71, its vertical shaft 72, intermittent clutch 73, feed arm 74 and feed bar 75 which is connected with the rock shaft. Reverse movement or back lash of the driven portion of the clutch 65 is prevented by the 25 clutch part 76. Similarly, a clutch part 77 prevents any reverse movement of the driven portion of the intermittent clutch 73. The clutch part 76 is held in a stationary position by the 30 horizontally extending arm 76' having a bifurcated end to receive the fixed pin 76a extending downwardly from the base 58.

The part 77 comprises a housing with an arm 78 slideable in an opening 79 in the base plate and in which the shaft of pinion 71 is journaled; 35 and this housing with its associated parts is movable toward and away from the carrier sufficiently to engage and disengage the pinion with the peripheral teeth of the carrier. The means for moving the pinion comprises a lever 80 which 40 embraces the shaft of the pinion and is mounted on a pivot stud 81 adjacent the locking tooth 82 at one end thereof. Said lever 80 at its opposite end has a finger engaging boss 83 and a pointer 84. When the pinion is engaged with the carrier, 45 the pointer indicates the "on" or driving position and the locking tooth 82 is out of engagement with the carrier. With the pinion 71 in engagement with the carrier, the latter element will be driven from the rock shaft, simultaneously with the pinking ring and in synchronism therewith. When the pinion is disengaged from the carrier, the pointer indicates the "off" position and the locking tooth 82 will be engaged with the carrier, locking the carrier against 50 rotary movement. A locking pin 85 is associated with the boss of the lever and is engageable with suitable keepers in the base plate, whereby 55 releasably to lock the lever in both its "on" and "off" positions.

This embodiment of my invention is essentially characterized by the novel method which consists in progressively feeding the fabric in a rectilinear path in tangential relation to the cutter, rotating in a plane parallel to the plane of the fabric, while forcibly pressing the fabric upon the cutter teeth, and, concurrently with the rotation of the cutter, imparting a relative lateral movement between the cutter and fabric with respect to the line of feed. Thus the pinking cuts will 60 extend in a wavy or undulating line, symmetrical- 65 ly spaced from the seam.

As clearly shown in Figs. 4 and 5, the pressure roller 86 is, in its axial direction, of a length 70 to exert pressure peripherally upon the upstand- 75

ing teeth of the pinking ring in any position of the pinking ring throughout the range of the eccentric throw of the carrier. The pressure roller is preferably tapered in an axial direction, from 5 its outer end toward its inner end, as shown. It is carried by an arm 87 secured to the rock shaft 88 which is mounted upon bracket 89 upon the base plate. The rock shaft is adjustably controlled by the pressure regulating plate 90. For 10 the sewing and pinking operations, the work is preferably passed through a customary or approved folder-guide 91 which is suitably mounted upon the base plate.

The work is passed to the feed dog and stitching mechanism to move along the feed line 60 in the usual way, with the edge or edges to be pinked seized between the pressure roller and the pinking ring. If it is desired to produce a pinked undulating edge, it is only necessary to see that the 15 pinion 71 is in mesh with the carrier. On the other hand, if it is desired to produce a straight pinked edge, the pinion is moved out of mesh with the carrier after the carrier has been adjusted to that position in which the pinking ring 20 will operate laterally at a predetermined distance from the line of stitching.

While I have illustrated and described the preferred forms of construction for carrying my invention into effect, these are capable of variation 30 and modification without departing from the spirit of the invention. I, therefore, do not wish to be limited to the precise details of construction set forth but desire to avail myself of such variations and modification as come within 35 the scope of the appended claims.

I claim:

1. In a pinking device, the combination of a carrier having rotary movement, and a rotatable pinking member eccentrically mounted on the 40 carrier, and means for locking the carrier against rotation when the pinking member is to be rotated.

2. In a pinking device, the combination of a support having a throat portion for feeding and 45 sewing mechanism, a carrier rotatably mounted on the support at one side of the throat portion, a pinking element eccentrically mounted on the carrier, said carrier through rotative movement being adapted to vary the distance between the 50 throat portion and pinking element.

3. In combination with a support, a shaft, a clutch operated by the shaft, a pinking cutter operated by the clutch, and a carrier disposed in the support to eccentrically rotate about the 55 shaft and in which said clutch and cutter are mounted for operation.

4. In a pinking device, a support, an actuating shaft, a clutch connected with the shaft for operation thereby, a pinking ring intermittently operated by the clutch, a carrier rotatably mounted in the support in eccentric relation to the shaft and in which said clutch and ring are arranged for operation, means associated with the support for adjusting the carrier, and means for locking 60 the carrier in adjusted position.

5. In a pinking device, a clutch, a pinking ring surrounding the clutch and operated thereby, a shaft for actuating the clutch, a support having a throat plate for sewing operations, a carrier on 70 the support, disposed to revolve adjacent said throat plate and operatively supporting said clutch and pinking ring in eccentric relation to the carrier axis, said carrier being adapted when revolved to vary the position of the pinking ring 75 with respect to said throat plate.

6. In a pinking device, the combination with a base having a throat portion for sewing operations, a carrier member rotatably mounted on the base adjacent the throat portion, and a pinking cutter movably mounted on the carrier and movable thereby so as to be given various positions with respect to the throat portion, said pinking cutter being operative independently of the carrier in any position to which it is moved by the 10 carrier.

7. A pinking device having, in combination, a base, a throat part for sewing operations, a carrier rotatably mounted on the base at one side of said throat part, a pinking member eccentrically mounted in the carrier and movable thereby so as 15 to vary its position with respect to the throat part accordingly as the position of the carrier is varied, a pressure device for applying pressure upon the pinking member, and means upon the base adjustably supporting the pressure applying device 20 to vary its position in correspondence with variation in the position of the pinking element.

8. A pinking device comprising a base, a throat part, a pinking ring, means on the base directly coacting with and supporting the ring 25 for rotation in a horizontal plane, means for adjusting said supporting means to vary the position of the ring with respect to the throat part, and means for rotating the ring.

9. A pinking device comprising a base, a rotary 30 pinking ring, a rotary adjusting member for the ring, and means for simultaneously and independently rotating the ring and member, said member being operatively mounted on the base to vary the position of the ring with respect to the 35 material being pinked.

10. A pinking device comprising a base, a rotary pinking ring, a rotary adjusting member for the ring, power means, transmission operated thereby for rotating the ring, transmission operated by the power means for rotating the adjusting member, including a disconnectible part, said member being mounted on the base to vary the position of the ring with respect to the material being pinked, and manually operated means for 45 controlling the disconnectible part.

11. A pinking device having a rotary support for the pinking means and a driving member for engaging and disengaging the support, in combination with an operating lever for controlling the 50 engagement and disengagement of the driving member and having means for locking the support, only, when the driving member is in disengaged position.

12. A pinking device having a rotary pinking 55 member, a rotary support for said member, a source of power, transmission means for rotating the member from the source of power, transmission means for rotating the support from the source of power, said last transmission means including a shiftable transmission part, and locking means, automatically operated when said part is shifted to an inoperative position, to lock said support against rotation.

13. A pinking device comprising an endless rotary pinking ring, a rotary carrier in which the ring is eccentrically mounted to rotate in any position of the carrier, means for simultaneously rotating the ring and carrier, and manually operated means for holding the carrier against rotation in any selected position thereof without interfering with the operation of the ring.

14. In a pinking device, a base with an opening, a rotary shaft extending thereto, a rotary carrier in eccentric relation thereto on the base with 75

a hub-portion in said opening and accommodating said shaft, and a pinking ring supported by the carrier and rotated from said shaft.

15. In a pinking device, the combination with a feed mechanism having to and fro movement and a shaft actuated thereby, of a base, a carrier rotatably mounted on the base having a hub-portion accommodating said shaft, a pawl plate on the carrier secured to and actuated by said shaft 10 and carrying a plurality of pawls, a pinking ring eccentrically mounted on the carrier and intermittently rotated by said pawls, and means for rotating said carrier, to variably position said pinking ring in respect to the work.

15. 16. In a pinking device, the combination of a pinking ring and carrier therefor mounted for relative eccentric rotation, a shaft for actuating the pinking ring, a pinion for actuating the carrier, feed mechanism having to and fro movement, transmission including an intermittent clutch for operating said shaft from said feed mechanism, transmission including an intermittent clutch for operating said pinion from said feed mechanism, and means mounting said pinion 20 permitting it to be moved laterally toward and away from said carrier for engagement and disengagement, respectively, therewith.

17. In a trimming device, two independently rotatable members having coacting means, whereby 30 relative rotation of said members imparts a concurrent planetary movement to one of said members, said latter member having trimming means, and power operated driving means for each of said members.

35. 18. In a trimming device, two independently rotatable members having coacting means, whereby relative rotation of said members imparts a concurrent planetary movement to one of said members, said latter member having trimming 40 means, power operated driving means for each of said members, and means for rendering the driving means for the other member inoperative and locking said member in a stationary position.

19. In a trimming device, a trimming member, 45 an adjusting member therefor, means for mounting said members to rotate in a common plane, and means operatively controlled by the adjusting member for imparting a planetary bodily movement to said trimming member.

50. 20. In a trimming device, a trimming member, an adjusting member therefor, means for mounting said members to rotate in a common plane, means operatively controlled by the adjusting member for imparting a planetary bodily movement to said trimming member, means for independently rotating said members, and means for locking the adjusting member against rotation.

21. In a trimming device, a rotary cutter having a movably supported axis, and means for 60 bodily shifting said cutter in its plane of rotation to position the same for effective operation with respect to a selected part of the work being trimmed.

22. In a trimming device, a rotary cutter, and 65 means for bodily shifting said cutter in its plane of rotation to position the same for effective operation with respect to a selected part of the work being trimmed, said means including a rotary member eccentrically connected with said cutter.

70. 23. In a trimming device, a rotary cutter, a rotary member eccentrically connected with said cutter for shifting the cutter in its plane of rotation to position the same for effective operation with respect to a selected part of the work being 75 trimmed, means for intermittently rotating said

cutter, and means for concurrently imparting rotation to said member.

24. In a trimming device, a rotary cutter, and means for bodily shifting said cutter in its plane of rotation to position the same for effective operation with respect to a selected part of the work being trimmed, said means including an independently rotatable member, eccentrically associated with said cutter and directly coacting therewith. 10

25. In a trimming device, a rotary cutter, means for bodily shifting said cutter in its plane of rotation to position the same for effective operation with respect to a selected part of the work being trimmed, said means including an independently rotatable member, eccentrically associated with said cutter and directly coacting therewith, and operator controlled means for optionally imparting rotation to said member, or locking the same in a stationary position relative to the cutter. 15

26. In a trimming device, a cutter mounted to rotate in a horizontal plane, means for rotating said cutter, and means for imparting a planetary bodily movement to said cutter, to vary 25 the position of effective operation of said cutter with respect to a selected part of the work being trimmed.

27. In a trimming device, a cutter mounted to rotate in a horizontal plane, means for rotating said cutter, and concurrently operating means for imparting bi-directional planetary bodily movements to said cutter, to continuously vary 30 the position of effective operation of said cutter with respect to a selected part of the work being trimmed.

28. In a trimming device, a cutter mounted to rotate in a horizontal plane, means for rotating said cutter, and relatively adjustable means peripherally coacting with said cutter to impart 40 a planetary bodily movement thereto and vary the position of effective operation of said cutter with respect to a selected part of the work being trimmed.

29. In a trimming device, a cutter mounted to 45 rotate in a horizontal plane, means for rotating said cutter, and relatively adjustable means mounted in circumscribing, directly coacting relation with said cutter, to impart a planetary bodily movement thereto and vary the position of effective 50 operation of said cutter with respect to a selected part of the work being trimmed.

30. In a trimming device, a cutter, an adjustable member, means for mounting said cutter and member for relative coacting rotation in eccentrically related orbits, means for rotating the cutter, and means for rotating said adjustable member to position said cutter for effective operation with respect to a selected part of the work being trimmed. 55

31. In a trimming device, a cutter, an adjustable member, means for mounting said cutter and member for relative coacting rotation in eccentrically related orbits, means for rotating the cutter, and operator controlled means for optionally imparting rotation to said adjusting member or to lock said member in an adjusted 60 position relative to the cutter.

32. In a trimming device, a rotatable cutter having an annular series of cutting teeth, and 70 means coacting with the cutter and controllable at the will of the operator to variably shift the path of operation of the cutter teeth with respect to a selected part of the work being trimmed.

33. In a trimming device, a rotatable cutter 75

5 having an annular series of cutting teeth, adjusting means coacting with the cutter, and operator controlled means to cooperate with said adjusting means and optionally position the cutter teeth in a predetermined fixed operating path, or, concurrently with the rotation of the cutter, continuously shift said operating path of the cutter teeth with respect to a selected part of the work being trimmed.

10 34. The method of edge pinking fabrics which consists in progressively feeding the fabric in a rectilinear path, with an edge thereof in tangential relation to a circular cutter rotating in a plane parallel to the plane of the fabric and in contact with an annular series of cutting teeth 15 on said cutter, and, concurrently with the rotation of the cutter, imparting relative shifting movement between said cutter and fabric laterally with respect to the feed path of the fabric, to thereby produce an undulating pinked edge on the fabric.

15 35. The method of edge pinking fabrics which consists in progressively feeding the fabric in a rectilinear path, with an edge thereof in tangential relation to a circular cutter rotating in a plane parallel to the plane of the fabric and in superimposed contact with certain of an annular series of cutting teeth on the upper face of said cutter, forcibly pressing the fabric upon said 20 cutter, and, concurrently with the rotation of the cutter, imparting relative shifting movement between said cutter and fabric laterally with respect to the feed path of the fabric, to thereby produce an undulating pinked edge on the fabric.

teeth, and, concurrently with the rotation of the cutter, imparting relative shifting movement between said cutter and fabric laterally with respect to the feed path of the fabric, to thereby produce an undulating pinked edge on the fabric. 5

36. The method of edge pinking fabrics which consists in progressively feeding the fabric in a rectilinear path, with an edge thereof in tangential relation to a circular cutter rotating in a plane parallel to the plane of the fabric and in contact with an annular series of cutting teeth on said cutter, and, concurrently with the rotation of the cutter, bodily shifting said cutter laterally with respect to the feed path of the fabric, to thereby produce a pinked edge of desired design 15

20 37. The method of edge pinking fabrics which consists in progressively feeding the fabric in a rectilinear path, with an edge thereof in tangential relation to a circular cutter rotating in a plane 25 parallel to the plane of the fabric, and in superimposed contact with certain of an annular series of cutting teeth on the upper face of said cutter, forcibly pressing the fabric upon said teeth, and, concurrently with the rotation of the cutter bodily shifting said cutter laterally with respect to the feed path of the fabric, to thereby produce a pinked edge of desired design on the fabric.

VICTOR J. SIGODA.
